UNITED STATES PATENT OFFICE.

ALLAN E. ALGER, OF LORAIN, OHIO.

VARIOCOUPLER.

Application filed August 16, 1923. Serial No. 582,179.

To all whom it may concern:

Be it known that I, ALLAN E. ALGER, a citizen of the United States, and a resident of Lorain, in the county of Lorain and State of Ohio, have invented certain new and useful Improvements in Vario-couplers, of which the following is a specification.

This invention relates to improvements in variocouplers.

10 The present invention more particularly relates to mounting means for vario-couplers employed in wireless telephony. The object of the invention is to provide means whereby the rotor and stator coils or units 15 of a vario-coupler may be mounted upon a panel with a minimum of parts and in an efficient and durable manner.

It is also an object of the invention that the mounting means permit a compact 20 assembly of a vario-coupler and that the rotor will not be subject to getting out of adjustment.

Other objects will hereinafter appear in the detail description to follow.

25 The invention is illustrated by way of example in the accompanying drawing, in which:

Figure 1 is a view in side elevation of a vario-coupler mounted upon a panel in accordance with the present invention and with parts broken away to more clearly illustrate the same.

Figure 2 is a perspective view of the mounting means for the rotor and stationary coils.

Referring to the drawings more particularly P indicates a panel, and C a casting upon which there is mounted the rotor R and stator or stationary coil S.

40 More particularly the casting C comprises a cylindrical body portion 10 which terminates at its one end in enlargement 11 with which there is formed a base flange 12. The enlargement 11 is formed with an arm 13 which extends downwardly and less than 90° to the body portion 10. The arm 13 is preferably of the length and shape shown and provided with a plurality of screw receiving openings 14. The base

45 flange 12 is also provided with a plurality of screw receiving openings adjacent its free edge and preferably the inner face of this flange is machined. The body member 10 has extending its entire length a bore 16 and also this member is provided adjacent its end with a transverse groove 17.

The stationary coil S may consist in a cylindrical shell 18 upon which the winding 19 of suitable wire is placed. The rotor R may also consist of a cylindrical shell 20 and winding 21 and of the diameter shown. It is to be understood however that the construction of the stationary coil and the rotor need not be as shown as other forms may be used.

65 The stationary coil S may be secured to the arm 13 of casting C by screws 20 or the like. The rotor is supported within the stationary winding and normally it may assume the position shown in Figure 1. The rotor is supported through a bar 21 and shaft 22. The bar 21 has each of its ends formed with an offset portion 22' which extend in opposite directions and each portion 22' terminates in a portion 23 extending at right angles thereto. The portion 23 may be secured to the rotor R by the means of bolts or the like as at 24.

70 A pin 25 extends from the shaft 22 at a point adjacent its forward end and said pin has its free end disposed in the groove 17. The forward end of the shaft 22 is threaded and extended through an opening in the bar 21 said opening occurring at a central point of the bar. The shaft carries a pair of lock nuts 26 whereby to hold the bar 21, a coil spring 25' is interposed between the forward end of member 10 and the innermost lock nut 26. The shaft 22 extends entirely through the member N and also through the panel P. A dial D having the usual knob K may be secured to the outer end of shaft 22. The casting is secured to panel P by machine screws or the like as at 27.

75 By turning the shaft 22 through the knob K the rotor R can be rotated from its full line position shown in Figure 1 to the dotted line position shown in the same view. The pin 25 limits the rotation of the rotor. The pin 25 also cooperates with the spring 25' for holding the rotor R in its adjusted position.

80 While the present invention is shown to mount a vario-coupler it is obvious that it may be employed for mounting similar radio frequency transformers and therefore it should be understood that the invention is not to be limited as illustrated and described as indicated by the appended claims.

I claim:

85 1. A device of the character described, comprising a bracket including a tubular

member terminating at its one end in a laterally extending base flange, an arm extending from the base flange disposed at an angle to the tubular member, a shaft 5 turnable within the tubular member, a coil supported by the arm, and a second coil supported by the shaft and within the first named coil.

2. In a device of the character described, 10 a casting or bracket comprising a tubular portion terminating at one end in a laterally extending base flange and formed at the last-named end of the tubular portion with a forwardly extending arm, said arm being 15 disposed at an angle to the tubular portion, a shaft journaled by the tubular portion, and a pin extended from said shaft and disposed in a transverse groove or slot in said tubular portion, whereby to limit the 20 turning movement of the shaft in either direction and also hold said shaft against longitudinal movement.

3. In a device of the character described, 25 a casting or bracket comprising a tubular portion terminating at one end in a base flange extending laterally therefrom, an arm extending forwardly with relation to the base flange and at an angle to the tubular portion, a shaft journaled by the tubular 30 portion, a pin extending laterally from the shaft and disposed in a transverse groove or slot in the tubular portion, whereby to limit the turning movement of the shaft and hold the same against longitudinal 35 movement, and means whereby to yieldably press the shaft in one direction.

4. In a device of the character described, 40 a casting or bracket comprising a tubular portion terminating at one end in a base flange extending laterally therefrom, an arm extending forwardly with relation to the base flange and at an angle to the tubular portion, a shaft journaled by the tubular portion, a pin extending laterally from the 45 shaft and disposed in a transverse groove

or slot in the tubular portion, whereby to limit the turning movement of the shaft and hold the same against longitudinal movement, a pair of lock nuts carried by the forward end of the shaft, and a coil spring 50 interposed between said nuts and the forward end of the tubular portion.

5. A vario-coupler comprising a rotatable shaft, a cross arm carried by the shaft and extending at right angles thereto, an offset portion at each end of the cross arm, a rotor secured to the offset portions of the cross arm and its longitudinal axis disposed at an angle to the similar axis of the shaft, and a stator encircling the rotor and having 60 its longitudinal axis extending parallel to the similar axis of the rotor.

6. A vario-coupler comprising a supporting bracket including a tubular portion, a base flange extending laterally from the one end of said tubular portion, whereby the bracket may be secured to a support, a shaft rotatably supported by the tubular portion, means for supporting a rotor at one end of the shaft so that its longitudinal axis is 70 disposed at an angle to a like axis of the shaft, and a stator encircling the rotor and having its longitudinal axis parallel to the similar axis of the rotor.

7. A vario coupler comprising a supporting bracket including a tubular portion, a base flange extending laterally from one end of said tubular portion, whereby the bracket may be secured to a support, a shaft rotatably supported by the tubular portion, means for supporting a rotor at one end of the shaft so that its longitudinal axis is disposed at an angle to a like axis of the shaft, an arm extending from the base flange and disposed at an angle to the longitudinal 80 axis of the shaft, and a stator supported by said arm and disposed with its longitudinal axis parallel to the similar axis of the rotor.

ALLAN ETHAN ALGER.
